UNITED STATES PATENT OFFICE.

MORRIS S. JACOBSON, OF NEW YORK, N. Y., ASSIGNOR OF ONE-HALF TO
RUSSELL GOLDMAN, OF SAME PLACE.

SAFETY-GUARD FOR RAZORS.

SPECIFICATION forming part of Letters Patent No. 592,611, dated October 26, 1897.

Application filed May 7, 1897. Serial No. 635,496. (No model.)

To all whom it may concern:

Be it known that I, MORRIS S. JACOBSON, a citizen of the United States, residing at New York, in the county of New York and State 5 of New York, have invented certain new and useful Improvements in Safety-Guards for Razors, of which the following is a full and complete specification, such as will enable those skilled in the art to which it appertains 10 to make and use the same.

This invention relates to safety-guards for razors; and the object thereof is to provide a device of this class which is simple in construction and operation and which may be 15 connected with an ordinary razor-blade; and with this and other objects in view the invention consists in the construction, combination, and arrangement of parts hereinafter described and claimed.

20 The invention is an improvement on that described and claimed in United States Patent No. 570,598, granted to me November 3, 1896, and is fully disclosed in the following specification, of which the accompanying drawings form a part, in which—

Figure 1 is a side view of a razor-blade provided with my improved guard and showing a portion of the handle; Fig. 2, an end view looking in the direction of the arrow a in 25 Fig. 1; Fig. 3, a section on the line 3 3 of Fig. 1; Fig. 4, a view similar to Fig. 1, showing a modification; Fig. 5, an end view looking in the direction of the arrow a^3 of Fig. 4, and Fig. 6 a section on the line 9 9 of Fig. 4.

30 In the drawings forming part of this specification the separate parts of my improvement are designated by letters of reference in each of the views.

In the drawings, A represents an ordinary 35 razor-blade having a shank a , and B a portion of the handle, and in the practice of my invention I provide a guard D, the outer end of which is bent inwardly or transversely of the end of the blade to form an arm d , and I also 40 provide a clamp G, which is oblong in form and which is adapted to be placed upon the back of the blade A and to clamp the same throughout its length, said clamp being provided with spring sides g , which press upon 45 the sides of the blade.

It will be understood that the back of the

blade is thicker than the body portion thereof, and the sides g of the clamp G are inwardly-curved or bent so as to grasp the same, as shown in Figs. 2 and 5. The upper portion of the clamp G, at the outer end thereof, is bent downwardly, as shown at g^2 , and the arm d of the guard projects into the end of the clamp and is pivoted therein, as shown at g^3 . The inner end of the guard D is also 50 curved upwardly to form a supplemental arm d^2 , which is provided with a loop d^3 , through which the shank a of the blade A passes, and the upper portion of the loop d^3 is pivotally connected with the end of the back of the 55 clamp G, as shown at d^4 . As thus constructed the guard D is free to swing transversely of the edge of the blade A, but only to a slight extent, the limit of the movement of the guard being determined by the sides of the 60 clamp G, which are struck by the arm d of the guard, and also by the side loop d^3 , which are struck by the sides of the shank a of the blade. This movement, however, is sufficient to permit of the free operation of the blade, 65 and at the same time the guard is held in such position with reference to the edge of the blade that the cutting of the face in the operation of shaving is practically impossible. This movement of the guard is effected 70 by slight pressure on the face in the operation of shaving, and when one side of the blade is placed against the face the guard swings past the edge and to the opposite side of the blade.

The same movement of the guard takes place when strapping or honing the razor, and this movement allows the razor to be cleaned or sharpened without removing the guard; but one feature of this invention consists in 75 the fact that the guard may be quickly and easily detached whenever necessary for sharpening or honing the blade.

In Figs. 4 to 6, inclusive, I have shown a modified form of construction, in which the arm d of the guard is passed upwardly through the end of the clamp G and pivoted thereto, as shown in Fig. 1, by means of the pivot-pin g^3 , and the arm D is provided with a plurality of perforations through which said pivot-pin 80 may be passed, and thus the position of the guard D may be adjusted with reference to

the edge of the blade. The arm d^2 is formed into a loop or yoke d^3 , as in Figs. 1 and 3, and the sides of said loop or yoke are projected upwardly and provided with transverse perforations through which the pivot-pin or bolt d^4 is passed, and the end of the clamp G is provided with an upwardly-directed shoulder d^6 , through which said pivot-pin or bolt also passes, and the sides of the loop or yoke d^3 are also provided with a plurality of perforations, and this end of the guard may also, therefore, be adjusted with reference to the edge of the blade. The operation of this form of construction will also be similar to that shown in Figs. 1 to 3, inclusive, as hereinbefore described, and it will be seen that the principle of the construction and operation in each of the modifications herein described and illustrated is the same.

Having fully described my invention, I claim as new and desire to secure by Letters Patent—

1. A guard for the blade of a razor adapted to be detachably connected therewith and consisting of a rod or bar which extends longitudinally of the edge of the blade, and a clamp which is adapted to be connected with the back of the blade, said clamp being provided with side plates which are adapted to grasp the side of the blade, the outer end of said rod or bar being provided with an angular arm which extends into or through the outer end of said clamp, and is pivotally connected therewith, and the end of said rod or bar adjacent to the shank of the blade being also provided with an arm which is provided

an arm which is provided with a yoke or loop through which the said shank passes, said loop or yoke being pivotally connected with the back of the said clamp at the end thereof, substantially as shown and described. 40

2. A guard for the blade of a razor adapted to be detachably connected therewith and consisting of a rod or bar which extends longitudinally of the edge of the blade, and a clamp which is adapted to be connected with 45 the back of the blade, said clamp being provided with side plates which are adapted to grasp the side of the blade, the outer end of said rod or bar being provided with an angular arm which extends into or through the 50 outer end of said clamp, and is pivotally connected therewith, and the end of said rod or bar adjacent to the shank of the blade being also provided with an arm which is provided with a yoke or loop through which the said 55 shank passes, said loop or yoke being pivotally connected with the back of the said clamp at the end thereof, and said rod or bar being also adjustable toward or from the edge of said blade, substantially as shown and described. 60

In testimony that I claim the foregoing as my invention I have signed my name, in presence of the subscribing witnesses, this 5th day of May, 1897.

MORRIS S. JACOBSON.
